UNITED STATES PATENT OFFICE

2,641,995

BILLET MARKER

James E. Whittaker, Superior, Wis., assignor to
United States Steel Corporation, a corporation
of New Jersey

Original application February 28, 1946, Serial No.
650,924, now Patent No. 2,541,800, dated Febru-
ary 13, 1951. Divided and this application June
29, 1950, Serial No. 171,116

5 Claims. (Cl. 101—4)

1

The present invention relates to marking de-
vices which employ a pivotally mounted hammer
carrying stamps adapted to make an impression
in the upright end face of a billet or slab as it
moves on a conveyor table.

This application is a division of my co-pending
application Serial No. 650,924, filed February
28, 1946, which issued as Patent No. 2,541,800,
February 13, 1951.

One object of the invention is to provide an
arrangement in which no outside source of power
is required to operate the hammer, such opera-
tion being accomplished as a result of the travel
of the billet or the like.

Another object of the invention is to provide
adjustable means for mounting the hammer to
suit different thicknesses of billets or the like.

A further object is to provide a swivel head on
the hammer which carries the marking stamps
so that the head will adjust itself automatically
to suit the angle of cut on the end face of the
billet or the like.

A further object is to provide means whereby
the swivel head can be shifted to different posi-
tions so as to stamp either a horizontal or di-
agonal line of identifying characters on the up-
right end face of the billet or the like.

Another object is to provide means to prevent
rebound of the hammer, thereby assuring that
the stamps will always be in proper position for
impact with the oncoming billet or the like.

An additional object is to provide means to
facilitate bodily changing the hammer and also
the stamps carried thereby.

Another object is to provide the hammer with
a roller adapted to ride on the billet and prevent
wear.

A further object is to construct and arrange
the parts hereinafter shown and described so that
individually and in combination they effectively
perform the functions set forth.

The above and further features of the invention
will be fully apparent from consideration of the
following detailed description and the ap-
pended claims when read in connection with the
accompanying drawings, in which:

Figure 1 is a side elevation of a billet marking
machine illustrating a preferred embodiment of
the invention;

Figure 2 is an end view of Figure 1;

Figure 3 is a section taken substantially along
the line III—III of Figure 2;

Figure 4 is a detail section of a snubber for
preventing rebound of the hammer;

Figure 5 is a fragmentary detail of the ad-
justable pivotal mounting for the hammer;

2

Figure 6 is a front elevation of Figure 5;
Figure 7 is a fragmentary detail view of the
stamp-carrying end of the hammer;

Figure 8 is a sectional view on line VIII—VIII
of Figures 2 and 7;

Figure 9 is a detached detail of the stamp
holder;

Figure 10 is an end view of the stamp holder;

Figure 11 is a detail of one of the stamps re-
moved from the holder of Figure 9; and

Figure 12 is an end view of one of the stamps.

Referring in detail to the drawings, the ma-
chine embodying the present invention is adapted
to apply identifying marks such as numbers or
combinations of numbers and letters to the up-
right front edge face of each of a plurality of

billets or slabs while they are traveling longi-
tudinally at a comparatively high rate of speed.
The machine shown includes a frame member

10 which forms part of a conventional run-out
table equipped with a number of suitably driven
rolls 12 which serve to move the billets B in the
direction of the arrow in Figure 1. As each
billet reaches the marking station, it is adapted

20 to have an identifying number impressed in the
upright end face b thereof. The present invention
relates to an improved simple, rugged mech-
anism which is entirely automatic and which re-
quires no outside source of power to operate the

25 marking hammer.

Mounted in juxtaposition to the run-out table
I provide a suitable standard 14 which near its
top supports an angle bar 16 on which is mounted
a bearing 18 for a shaft 20 adapted to be held

30 in various fixed positions of adjustment by a set
screw 22 (Figure 6). Formed eccentrically on
the shaft is a journal shank 24 which forms a
pivotal mounting for a hammer lever 26 (Figure

35 5). Turning the shaft 20 in the bearing 18 ele-
vates or lowers the eccentric journal shank 24
so as to adjust the position of the holder 28 car-
ried by the head 30 at the free end of the ham-
mer. The eccentric journal 24 carries a collar

40 27 adjustably secured thereto by a suitable set
screw (Figure 5).

Near its outer end the journal shank 24 has a
45 groove 34 (Figure 5) for coaction with a plunger
36 which is secured to the end of a rod 38 guided
in suitable apertures formed in brackets 40—42.

50 The plunger 36 slides in a guide slot formed in
bracket 42. A pin 44 pivotally connects rod 38 to
a link 46, which in turn is pivoted at 48 to the
upper end of a hand lever 50. Said lever has a
hand grip adapted to be actuated so as to lift

55 the rod 38 against the action of a compression
spring 52 mounted thereon between brackets 40

and 42 so as to permit quick withdrawal of plunger 36 from groove 34 formed in the journal shank. This arrangement facilitates the operation of quickly changing hammers without interfering with the marking of billets as they travel along the roll table in succession at a high speed, it being understood by those skilled in the art that a great number of billets from a single heat of steel are usually given the same identifying number. Thus when the billet from a different heat comes along, it is necessary either to stop the movement or to change the marking means quickly. The present invention makes it unnecessary to stop the movement of the billets, and greatly facilitates this quick change of the marking means by providing an arrangement in which one hammer can be removed bodily and another hammer inserted in its place, the latter having previously had the proper identifying numbers or characters set up in the stamp holder thereof corresponding to the new heat of steel.

As the hammer lever 26 moves in its normal arcuate path, it is guided between a continuous quadrant plate 54 and two short arcuate guide plates 56 and 58 secured at 60 and 62 to the angle bar 16 and the upright stand 14 (Figure 1). At the time of making the change from one hammer to another, the lever 26 is swung approximately to the dotted position of Figure 1, whereupon the hand grip 50 is clasped so as to withdraw the plunger 36 from the groove 34 and thus permit the hammer lever 26 to be removed by lateral movement from the space between the arcuate plates 56 and 58. By a similar reverse operation, a substitute lever 26 can be quickly mounted on the journal shank 24.

At its outer extremity, the hammer is forked for the reception of a roller 64 rotatably mounted on a bolt 66 penetrating the forked portion. The hammer head is formed with a semispherical cavity or seat 68, forming a self-centering swivel mounting for the stamp holder indicated as a whole at 70 (Figure 9). This stamp holder includes a shank portion 72 which is adapted to pass through a flared hole 74 in the head so as to permit limited relative swiveling action of the holder (Figure 8). Loosely fitted over the shank 72 is a washer 76 against which a compression spring 78 presses, the other end of this spring engaging a washer 80 which is adjustably positioned by a nut 82 screwed on the threaded end of the shank 72.

The stamp holder as shown in Figures 8 and 9 includes an enlarged spherical body 84 of approximately the same radius as the seat 68. The body 84 carries a radially extending stud 86 adapted to be selectively engaged with the notches 88, 90, or 92 (Figure 7). When the stud 86 is engaged with the notch 88, the stamps will be positioned to impress a substantially horizontal line of identifying characters on the end face b of the billet, and when the said stud 86 is engaged with either the slots 90 or 92, the lines of characters will be impressed obliquely, along lines making a 45° angle with the horizontal, for example, as will be understood from the drawings.

A plurality of marking stamps, such as shown at 96 in Figures 11 and 12, are removably secured in line in a slot or recess 94 formed in the enlarged body 84 of the holder. The butt ends 98 of the stamps contact a flattened portion 100 of a hardened steel wear-resisting butt pin 102 suitably secured in a bore in the relatively softer steel body 84 of the holder. The front ends of the stamps have type faces 104 in the forms of

numbers or letters. At a point intermediate the type face and the butt end, each stamp has an arcuate recess 106 for coaction with a keeper pin 108. This pin has an operating knob 110, and at 5 the end opposite the knob carries a compression spring 112 adapted to impositively hold it in. The keeper pin has a flattened portion 114. As thus arranged it is possible to remove the stamps quickly and easily, and insert others having different type faces. To effect such a change it is necessary merely to turn the keeper pin so as to bring the flattened portion 114 opposite the notch 106 in the stamp, thus permitting the stamp to fall out, it being understood that normally the cylindrical body portion of the keeper pin snugly engages the arcuate slot 106 in the several stamps.

The machine is equipped with snubbers 116 and 118 secured respectively to the angle bar 16 and the standard 14 (Figures 1 and 3). These snubbers are of duplicate construction, and a description of one will suffice for both. As shown in Figure 4, each snubber includes a pneumatic cylinder 120 having a piston 122 working therein and functioning as an air cushion. The piston has a forwardly extending portion 124 and a rearwardly extending shank 126. The shank 126 carries a bushing 128 seated against which there is a compression spring 130 whose opposite end 15 engages the wall 132 of a screw cap 134, threaded at 136 to a plug 138 which is screwed into one end of the cylinder 120.

In operation, rollers 12 of the conveyor table propel the billets at a speed of about 600 feet per minute. As the leading end b of each billet strikes the stamps 96, these stamps make a deep identifying impression in the upright end face of the billet, it being understood that the billets on the run-out table are in a red hot or incandescent state. If the billet has not been cut truly square, the die holder swivels on its spherical head to a position parallel to the billet end, and spring 78 holds it in this position. Upon impact, the hammer swings up in an arc about journal 24. At the upper end of its stroke the hammer strikes the piston rod of snubber 116, which lessens the shock and prevents rebound. It is desirable to prevent rebound at this point, since this allows for more time for a billet to pass through under the hammer head 30. While the hammer arm is up, a billet passes, and when the hammer arm falls the roller 64 strikes and rides on the top surface of the billet, as indicated in dotted lines in Figure 1. After the billet passes beyond the roller 64, the hammer arm falls to the full-line position of Figure 1 and the air-cushioned piston of the snubber 118 prevents its rebounding. Preventing rebound at this stage is considered more important than the prevention of rebound on the upswing. When the billets are traveling at a high rate of speed and are from 8 to 12 feet apart, any rebound would cause the stamps to engage the billets at a point too high on the end face or to miss them altogether.

While I have described quite precisely a construction and arrangement of parts which an actual reduction to practice shows is highly desirable, it is not to be construed that I am limited thereto, since various modifications and substitutions of equivalents may be made without departure from the scope of the invention as defined in the appended claims.

I claim:

1. A billet marking apparatus comprising a standard adapted to be supported on a run-out

table, a horizontal shank supported on said standard, a hammer lever journaled on said shank, means releasably retaining said lever on said shank, arcuate guide means supported on said standard and guiding the path of said lever and having an opening through which said lever may be withdrawn on release of said retaining means, die holding means mounted for universal movement adjacent the free end of said lever, a die removably fixed in said die holding means and adapted to be struck sharply by the leading end of each billet traveling on the run-out table and thus to mark billet ends, and a roller mounted on the free end of said lever beyond said die holding means and having its circumference extending beyond the free end of said lever for riding over a billet passing beneath the lever.

2. A billet marking apparatus comprising a standard adapted to be supported on a run-out table, a horizontal shank supported on said standard, a hammer lever journaled on said shank to swing through a horizontal arc, retractable means on said lever engaged with said shank for releasably retaining said lever on said shank, arcuate guide means supported on said standard and guiding the path of said lever and having an opening through which said lever may be withdrawn on retraction of said retaining means, snubber means supported on said standard and limiting swinging of said lever and preventing rebound, die holding means mounted for limited universal movement adjacent the free end of said lever, a die removably fixed in said die holding means and adapted to be struck sharply by the leading end of each billet traveling on the run-out table and thus to mark billet ends, and a roller mounted on the free end of said lever beyond said die holding means and having its circumference extending beyond the free end of said lever for riding over a billet passing beneath the lever.

3. A billet marking apparatus comprising a standard adapted to be supported on a run-out table, bearing means supported on said standard adjacent the top thereof, a free-swinging lever journaled on said bearing means to turn on a horizontal axis, a die mounted on said lever adjacent the free end thereof and adapted to be struck sharply by the leading end of each billet traveling on the run-out table and thus to mark the billet ends, a pair of arcuately spaced snubbers supported on said standard and adapted to be engaged by said lever at opposite ends of its swing for limiting the swinging movement thereof and preventing rebound, and a roller

mounted on the free end of said lever beyond said die and having its circumference extending beyond the free end of said lever for riding over a billet passing beneath the lever.

5 4. A billet marking apparatus comprising a standard adapted to be supported on a run-out table, a journal shank supported on said standard adjacent the top thereof and having a groove around its outer portion, a free swinging lever pivotally mounted on said shank, a retractable plunger carried by said lever and normally riding in said groove for holding said lever on said shank, means for retracting said plunger and thus permitting ready removal of said lever, a die mounted on said lever adjacent the free end thereof and adapted to be struck sharply by the leading end of each billet traveling on the run-out table and thus to mark the billet ends, a pair of arcuately spaced snubbers supported on said standard and adapted to be engaged by said lever at opposite ends of its swing for limiting the swinging movement thereof and preventing rebound, and a roller mounted on the free end of said lever beyond said die and having its circumference extending beyond the free end of said lever for riding over a billet passing beneath the lever.
